UNITED STATES PATENT OFFICE.

JOSEPH B. FEY, OF CINCINNATI, OHIO.

HORN ATTACHMENT.

Application filed June 20, 1921. Serial No. 478,893.

To all whom it may concern:

Be it known that I, JOSEPH B. FEY, a citizen of the United States of America, and a resident of Cincinnati, in the county of 5 Hamilton and State of Ohio, have invented a new and useful Improvement in Horn Attachments, of which the following is a specification.

An object of my invention is to provide 10 means whereby the operator of an automobile having a push button controlling the circuit embracing the signal horn located substantially in the center of the steering wheel, can actuate the push button without 15 removing his hand from the steering wheel.

Another object is to provide a device for 20 the purpose stated that may be readily mounted on various types and makes of automobiles, wherein the push button is located as described.

These and other objects are attained by the means described herein and disclosed in the accompanying drawings, in which—

Fig. 1 is a plan view of a steering wheel 25 having mounted upon it a device embodying my invention.

Fig. 2 is a sectional view on line 2—2 of Fig. 1.

Fig. 3 is an enlarged sectional view on 30 line 3—3 of Fig. 1.

Fig. 4 is a plan view of modified form of my invention.

Fig. 5 is an enlarged sectional view on line 5—5 of Fig. 4.

35 My invention comprises a plate A having a yoke formed at one end thereof, the branches α of which yoke are adapted to be mounted upon the legs b of the quadrant B by means of brackets α' . The brackets comprise an upper jaw α^2 having a blind bore α^3 therein, through which a screw α^4 may extend, the head of the screw lying upon the upper surface of the jaw, and a lower jaw α^5 having a threaded bore α^6 therein, in 40 which the screw α^4 engages. The opposed faces α^9 formed on the jaws are rounded so that the jaws may be mounted on the quadrant of any automobile. A finger α^{10} is formed at the free end of each jaw to retain 45 the jaws on the quadrant. The branches α have formed in them, near their ends, a blind bore α^7 through which the screw α^4 extends. The screw α^4 serves to mount the plate upon the jaws and to also mount the 50 jaws upon the quadrant. The plate has a jaws upon the quadrant. The plate has a threaded slot α^8 extending therethrough. A

bent rod D has one of its legs d extending through the slot α^8 and is adjustable longitudinally of its length through said slot by means of a threaded portion b' formed on 60 the leg d and upon which threaded portion is mounted the nut lock d^2 . It is preferable to form a boss d^3 upon the plate at this place and to have the perforation α^8 therethrough, in order to give a firmer seat to the rod D. 65 If desired the slot α^8 may be elongated radially to permit radial adjustment of the rod D. A second lock nut would then be disposed below the plate to cooperate with the first mentioned lock nut to position the 70 rod D radially in relation to the push button. The other leg d^3 of the rod D extends substantially parallel with the plate A and its free end is adapted to lie immediately over and upon the push button C disposed 75 substantially central to the steering wheel E. The free end of the plate A terminates immediately adjacent the steering wheel E and in such proximity thereto that an operator can exert a downward pressure on the 80 free end of the plate by means of his thumb without removing his hand from the steering wheel or weakening his grip upon the steering wheel.

If desired the branches of the yoke may 85 be pivotally mounted upon the brackets α' . The structure shown in Figs. 1, 2 and 3 however permit a very slight play of the yoke branches upon the screws α^4 , which play is sufficient to permit the necessary depressing of the plate A required to actuate the push button. The push button C is 90 spring actuated as is common practice, and the return of the spring to its normal position after the releasing of the pressure thereupon will suffice to return the plate to its 95 normal position.

Normally the parts are in the relation as shown in Fig. 2. When an operator desires to actuate the push button C, a downward 100 pressure exerted upon the free end of the plate A is transmitted to the rod D and from the rod to the push button C, whereby the push button is moved downwardly against a yielding resistance forming a part of the 105 push button, which push button construction is well known in the art, thereby causing the push button to complete an electrical circuit embracing a signal horn or other device. When the plate A is released from 110 this downward pressure, the yielding means in the push button mechanism moves the

push button upwardly and this upward movement of the push button is transmitted to the rod D and the plate A, wherefore the parts resume their normal positions. 5 The rod D may be readily adjusted longitudinally of its length to permit adjusting of the device on the various automobiles to which it may be applied and having a push button disposed as described. 10 In Figs. 4 and 5 I show a modification of my device, to be employed when the legs of the quadrant are so disposed that the center of movement of the plate A would be located between the push button and the operator's 15 thumb. This condition will exist where the quadrant legs extend at right angles to one another if the form of my invention shown in Fig. 1 is used. My modified form meets this condition by pivotally mounting the 20 free ends of the yoke branches upon the lower or main jaws a^{11} of the brackets a' , by means of suitable screws or pivots a^{12} . The upper or auxiliary jaws a^{14} are pivotally mounted on the main jaws by means 25 of the screws a^{13} which are tightened or set to clamp the jaws upon one another. The pivotal connections a^{12} permit moving of the said center of movement of the plate beyond 30 the push button. It is preferable in my modified form to make the lower jaw longer than the upper jaw to permit ready mounting of the device upon various types of 35 quadrants having their legs disposed at angles at or near 180° . In these views I also show the rod D as being radially adjustable.

What I claim is:

1. In a push button actuating device for 40 automobiles having a signal controlling push button mounted substantially central to the steering wheel, the combination of a plate, branches formed at one end of the plate, brackets adapted to mount the branches upon the steering wheel quadrant so as to dis-

pose the other end of the plate adjacent the rim of the steering wheel, and a rod mounted 45 on the plate engaging the push button adapted to transmit motion between the plate and the push button.

2. In a push button actuating device for 50 automobiles having a signal controlling push button mounted substantially central to the steering wheel, the combination of a plate extending substantially between the rim of the steering wheel and the center of the wheel and having an elongated slot 55 extending longitudinally thereof, branches formed on the centermost end of the plate, brackets mounting the branches upon the steering wheel quadrant, a rod adjustable radially and longitudinally through the slot 60 in the plate engaging the push button adapted to transmit a downward pressure exerted upon the free end of the plate to the push button and to transmit an upward pressure from the push button to the plate. 65

3. In an attachment for a push button mounted substantially central to an automobile steering wheel, the combination of a slotted plate, a yoke formed on one end of the plate, brackets adapted to be mounted 70 upon an automobile quadrant and to mount the yoke branches upon the quadrant, whereby the plate is supported in substantially the same plane with that in which the steering wheel is rotatable, a rod adjustable through the slot in the plate 75 mounted on the plate and engaging the push button whereby pressure upon the plate may be transmitted to the push button, and pressure upon the push button may be transmitted to the plate.

In testimony whereof, I have hereunto 80 subscribed my name this 17th day of June, 1921.

JOSEPH B. FEY.
